ELECTRIC BELL

Filed Oct. 9, 1923

UNITED STATES PATENT OFFICE.

ARTHUR C. GAYNOR AND EDWIN G. GAYNOR, OF STRATFORD, CONNECTICUT; SAID
EDWIN G. GAYNOR ASSIGNOR TO SAID ARTHUR C. GAYNOR.

ELECTRIC BELL.

Application filed October 9, 1923. Serial No. 667,475.

This invention relates to an electric bell and, more particularly, to a bell of simplified construction capable of being operated efficiently by either direct or alternating current.

Accordingly, an object of our present invention is to provide a bell or gong operating mechanism in which the losses of electric energy due to eddy currents and other losses associated with the use of alternating currents may be decreased or eliminated.

Another object of the invention is to provide a bell in which a maximum noise may be generated from a given gong with a minimum of electricity.

Other objects are, to provide a bell in which as much electric energy as possible is taken from the source, converted into the kinetic energy of the hammer, and in turn imparted to the gong with the least possible loss of energy in impact. Further objects of the invention are to provide improved contact means in an electric bell by which the electric current is tapped for a maximum time, of an electromagnet core of high permeability and a supporting frame in which eddy currents are reduced to a minimum. Additional objects of the invention are to provide an improved and simple type of hammer and arm, and a supporting base of simple and inexpensive construction.

With these and other objects in view, the invention comprises the bell and actuating mechanism disclosed and set forth in the following specification and claims.

The various features of the invention are illustrated in the accompanying drawings in which;

Fig. 1 is a plan view, partly in section, of a bell embodying a preferred form of the invention the gong being illustrated in dot and dash lines,

Fig. 2 is a longitudinal sectional view of the bell, taken on line 2-2 of Fig. 1,

Fig. 3 is a longitudinal sectional view of a portion of the bell actuating mechanism taken on line 3-3 of Fig. 1,

Fig. 4 is a perspective view of the hammer actuating mechanism,

Fig. 5 is a perspective view of a supporting frame for the hammer actuating mechanism, and

Fig. 6 is a detail view of a spring for actuating the hammer of the bell.

In the present invention, the striking por-

tion of the hammer is carried on an arm that is substantially rigid and inflexible under the impacts and impulses of the actuating mechanism so that the loss of energy in bending or flexing this arm is eliminated or reduced to a minimum. This arm is pivoted at one end on a supporting frame which also supports the actuating electromagnet in a position to act directly and effectively on the hammer arm at a point a considerable distance from the pivotal point, and the supporting frame and electromagnet are so proportioned as to fit into, and be readily retained in, an enclosing casing. The hammer arm is urged from the electromagnet by a spring mounted on the frame and pressing against the face of the arm. When the arm is pressed away from the electromagnet, the circuit is closed through a stationary contact supported on an insulated spring and a contact mounted on a leaf spring on the hammer arm positioned to press against and slightly displace the stationary contact when the arm is thrown away from the electromagnet. A sliding contact is thus provided thereby insuring a clean, effective contact and a period of contact of considerable length. This enables the electric current to pass through the electromagnet and to act on the hammer arm for a maximum portion of the period of vibration or oscillation. This arrangement also provides a very strong impulse of restitution or rebound, which throws the hammer away from the gong immediately after the stroke and thus prevents a dampening effect of the hammer on the gong. A high efficiency of the electromagnetic action is obtained by making the core of the electromagnet of a laminated structure and of metal of high permeability and by so slitting the supporting frame as to eliminate eddy currents thus avoiding loss of energy.

Referring more particularly to the accompanying drawings, the actuating mechanism embodying the invention is illustrated in connection with a gong 10 mounted on a base 12 of suitable construction. The actuating mechanism is contained within a cover 14 mounted on the base 12 in suitable manner preferably by means of lugs 16 extending from the corners of the cover through openings 18 in the base and peened or clinched under the face of the base.

The elements of the bell operating mechanism are mounted principally on a frame 20, which fits in the cover adjacent a side wall 21 and is held in place at one end against this wall by means of a core 22 of an electro-magnet 24 mounted on the back of the frame and spanning the distance from the back of the frame to the opposite or side wall 25 of the cover and at the other end by an indentation 26 in a wall 27 of the cover. The frame 20 is formed of a sheet of metal, preferably brass, stamped to form a back portion or supporting plate 28, on which the core 22 is mounted, a number of upper side members 29, lower side members 30 and spacing lugs 32 and 34 extending from the plate 28 to the upper wall of the cover and to the base respectively. The front edges of the side members 29 and 30 are notched 20 to receive a front plate or slab of insulating material 36 notched to fit into the notches of the side plate. The frame is shaped and adapted to fit into the front part of the cover with the slab 36 against the wall 21 25 and held tightly in position against the front wall of the cover by means of the electro-magnet core 22 mounted on the rear face of the back 28 of the frame and by the indentation 26.

30 The sheet of metal forming the frame 20 is also bent to form a pair of lugs or flanges 38 and 40 on which is pivotally supported an arm 42 which extends under the gong 10 and is provided with a striking hammer 44 positioned to strike the inner edge of the bell as the arm is vibrated. The hammer 44 may be of any suitable type. In the interests of cheapness and simplicity in construction and of durability, the hammer and arm are preferably stamped from a single sheet of heavy sheet metal, the hammer being pressed into the desired cone shape in the stamping operation in which the arm is formed. A pair of pintles 46 are formed as the arm is stamped out to extend sidewise from the opposite end of the arm 42 and be journaled in notches 48 in the lugs 38 and 40. These pintles may be easily inserted into the notches when the frame is out of the cover and are held in position in the notches by the side walls of the cover when the frame is inserted in the cover.

55 The arm 42 is intermittently vibrated to cause the hammer 44 to strike the gong 10 when the electro-magnet 24 and core 22 are energized and to be thrown out of contact with the gong by a suitable spring device when the energization of the electro-magnet is interrupted. This spring device is preferably formed of a flat or leaf spring 48 having a hooked end portion 50 adapted to be inserted in a notch 52 in the end of the plate 20 and return over the opposite face of the plate. The free end of the spring extends 60 towards the arm 42 and presses thereagainst

at a locality adjacent the electro-magnet core 22.

When the electro-magnet 24 is energized, it attracts the arm 42 directly, causing it to swing on the pivoting pintles 46 and causing the hammer 44 to strike the inner surface of the gong 10. The attractive force of the electro-magnet is exerted on the arm 42 at a locality intermediate the pivotal point and the hammer 44, and, if the arm 42 were very flexible, a considerable portion of the force of the electro-magnet would be exerted in flexing the arm before this force would be transmitted to the hammer. This lag in the transmission of the impelling force to the hammer would, in addition tend to hold the hammer in contact with the gong after the impact and thus tend to dampen the vibration of the gong, and deaden the sound. To obtain the maximum efficiency in the utilization of the electro-magnetic force generated in the electro-magnet, therefore, the arm 42 is made substantially rigid so that it suffers no substantial flexing under the forces exerted on it and transmits this force promptly and undiminished to the hammer 44, while at the same time permitting the returning force of the spring 48 to strengthen the rebound of the hammer as it strikes the gong and thus immediately 65 throw it out of contact with the surface of the gong. By making the arm 42 of the required stiffness, therefore, the forces of the electromagnet and of the spring 48 are as effective as though they acted directly on the 100 hammer 44.

The current for energizing the electro-magnet is supplied from a supply main 54 to a binding post 56, which is connected to the electro-magnet 24 by means of a conductor wire 58. From the electro-magnet 24, the current is returned through a conductor 60 to a contact supporting member 62 mounted on the plate of insulating material 36 and insulated from the cover 14. A spring 64 is mounted on the arm 42 to extend toward the contact supporting member 62 and is provided at its free end with a contact 66 adapted to contact with a stationary contact 68 mounted on the member 62 as the spring 48 swings the arm 42 away from the electro-magnet 24. When the contacts 66 and 68 are in contact the current returns through the spring 64 to the arm 42, which is in contact with the 110 cover 14. From the cover 14 the current is received by a return conductor 70 connected to the cover by means of a binding post 72.

The contact supporting member 62 provides a spring or resilient support for the contact 68 so that it is displaced slightly by the pressure of the spring 64. The displacement of the contact 68 depends on the force with which the arm 42 is thrown back and forth, thus affording a self adjusting 120

support for the contact 68 that enables the usual type of adjusting screw to be dispensed with. The displacement of the contacts also causes a slight sliding between 5 the contacts that keeps the contact surfaces clean and insures a contact. By means of this yielding contact, moreover, the contacts are in contact with each other for a longer portion of the period of vibration and a 10 larger quantity of current can be tapped from a given source. The contact support 62 is preferably formed of a U-shaped piece of metal 74 secured to the insulating plate 36 and the conductor 60 by means of a 15 rivet 76.

To increase the efficiency in transforming the electric energy of the current flowing through the coil 24 into magnetic force acting on the hammer arm 42, the core 22 is 20 made of a laminated structure and of a highly permeable metal. This is preferably done by bending a strip of permeable metal of the proper size into folds extending longitudinally of the core and pressing these 25 folds together into close contact, at the same time giving the folded mass an outer cylindrical shape as the folds are compressed together. As this operation may be carried out equally well with metals of different 30 properties, no difficulty is experienced in making the core of a metal of high permeability. The core is mounted on the plate 28 of the frame 20 by inserting its end in a hole 78 in the plate. The compressibility of the 35 laminated core aids materially in readily effecting a tight fit of the core in the hole 78 in the plate 20. The plate is slit at 80 from the hole 78 to the end of the plate to break the electric circuit through the plate about the 40 core and thus eliminate eddy currents about the plate as the magnetism through the core varies or is reversed in the case that alternating currents are used. The slit 80 also permits the hole to be very slightly enlarged 45 by spreading the slit and to contract on the end of the core 22 inserted therein and thereby provides a resilient and gripping hold on the core.

The gong and gong operating mechanism 50 may, of course, be mounted on any suitable base. The present invention, however, provides a base of particularly cheap, simple and durable construction by stamping the base of sheet metal and stamping a support-

ing post for the gong at the time that the 55 base is stamped out. This is done by bending the portion 82 beneath the gong upwardly at a right angle to the main portion of the base and extending it horizontally to form a flat lug 84 on which the gong 10 may be 60 mounted by means of a rivet or bolt.

As changes of construction could be made within the scope of our invention, it is intended that all matter contained in the above 65 description or shown in the accompanying drawings shall be interpreted as illustrative and not in a limiting sense.

Having described the invention, what we claim and desire to secure by Letters Patent is:

1. A device of the type described which comprises, an electromagnet core, and a base plate having a hole in which the end of said core is received and having a slit extending from said hole to the edge of said plate, permitting said hole to contract onto and hold the inserted end of the core.

2. A device of the type described which comprises, a casing, a frame mounted in said casing having a flat plate extending longitudinally of said casing and side walls, and a notch in the end of each side wall parallel to said plate, a vibrating arm having a pair of pintles pivoted in said notches and held in place by the adjacent wall of the casing, a leaf spring bent through a notch in and gripping said plate and pressing against said arm, and an electro-magnet on the opposite side of said plate.

3. An electric bell which comprises, a casing, a frame in said casing fitting against one side and the adjacent walls of said casing, an electro-magnet extending from said frame to the opposite wall of said casing holding one end of said frame in position, and an inward indentation positioned in an adjacent side wall to retain the adjacent end of said frame in position.

4. A device of the type described which comprises, a frame, a vibrating arm pivoted at one end of said frame, and a leaf spring pressing against said arm and having a hooked end engaged about the end of said frame, a covering casing for said frame and acting to hold said spring in position.
